MORRIS H. BENNETT, OF WATERBURY, CONNECTICUT, ASSIGNOR TO SCOVILL MANUFACTURING COMPANY, OF WATERBURY, CONNECTICUT, A CORPORATION OF CONNECTICUT

FLASH LIGHT

Application filed March 6, 1931. Serial No. 520,538.

This invention relates to flash lights and an object of this invention is to provide an improved form of light which will be simple in construction, reliable in operation and relatively cheap to manufacture and assemble.

This and other objects which will be apparent to those skilled in this particular art are accomplished by means of the invention 10 illustrated in the accompanying drawing which shows a partial sectional view of a flash light constructed in accordance with one embodiment of this invention.

In the particular embodiment illustrated, 15 the present invention is shown applied to a flash light of the so-called focussing type having a casing 5 threaded at one end to receive the head 6 carrying the usual reflector 7 and lens 8 mounted therein between an annular shoulder 9 formed on the head and a lens ring 10 which is threaded to the head so as to clamp the reflector and lens in position. The head also has the usual threaded 20 connection 11 by means of which it is secured in place upon the casing so as to permit longitudinal adjustment of the reflector with respect to a lamp 12 mounted in a lamp socket 13 secured to the adjacent closed end 25 14 of the casing 5. The lamp supporting end 14 of the casing is formed integrally with the casing by spinning or otherwise shaping the metal of the casing itself to form the closed lamp supporting end, the usual opening being left therein to permit the lamp 30 base 15 to extend into the interior of the casing to engage a contact strip 16 secured to and extending along the inner wall of the casing from which it is insulated by a suitable insulating strip 17.

The usual battery 18 is positioned in the casing and the center battery terminal 19 engages a second conductor strip 20 adjacent to the lamp engaging conductor strip 17 from which it is insulated by a suitable insulating strip 21. The conductors and insulating strips are mounted as a unit upon tubular clamping members 22 which are secured to the casing by suitable closed end 45 rivets 23. The battery engaging strip 20 is provided with an offset portion 24, shown

exaggerated in the drawing, and the insulating strip 21 terminates short of the end of the lamp engaging conductor strip 16 to provide exposed conductor portions which are adjacent to but spaced slightly from each other. A thumb switch which may be of any desired construction has an operating member 25 engaging a yieldable spring plate 26 interposed between it and the adjacent portion of the insulating strip 17 and having a central displaced portion 26' engaging the insulating strip 17, the arrangement being such that pressure on the switch member presses the spring plate downwardly and the depressed portion 26' moves the conductor strips into engagement with each other to connect the battery and lamp circuit. The end of the strip 16 is provided with a lip 27 or the like so that only a slight movement or flexing of the strip is necessary to produce a contact between it and the offset portion 24 of the battery engaging strip 20. Also, by extending the strip past the operating member 25 the movement of the contact pin 27 is increased relatively to the operating member.

Prior to being positioned within the casing, the insulating strips 17 and 21, the conductor strips 16 and 20, and the wear plate 26 are mounted upon the tubular members or rivets 22 to form a unitary assembly which can be positioned as a unit within the casing and secured thereto by the rivets 23 as above described. Insulating washers 28 are employed to insulate the conductor strips 25 from the tubular members 22. The lower end of the casing is closed by the usual screw threaded cap 29 through which connection is made between the casing and the base terminal of the battery which conducts the current to the side of the lamp through the closed end 14 and socket 13.

The assembly of conductor strips is so formed as to extend across the end 14 of the casing and is connected to the casing end by 50 a rivet on the side of the lamp socket opposite to that on which the main portion of the conductor assembly is mounted. As a result, the assembly is securely held against displacement and the offset portion 30 be- 100

tween the lamp base and the battery forms a cushion or buffer which protects the lamp against damaging blows by the battery.

It will be apparent that forming the closed 5 end 14 of the casing by suitably shaping the metal of the casing itself provides, in effect, a sealed end preventing the admission of moisture and the like to the interior of the casing and at the same time forms a conduct- 10 ing support for the lamp socket by means of which the current is carried to one terminal of the lamp.

I claim as my invention:

1. The combination in a flash light of a 15 casing, a lamp, a battery, separate conductor strips connected to said lamp and battery respectively, insulating means between said individual strips and between said strips and said casing, a resilient wear plate associated 20 with said strips, supporting means for securing said strips, said insulating means and said wear plate together to form a unitary assembly and means for supporting said assembly on the inside of said casing to permit 25 said lamp and battery to be connected, and operating means engaging said plate and movable to connect said strips to electrically connect said lamp and battery.

2. The combination in a flash light of a 30 metallic casing having a substantially closed end, a lamp supported on said closed end and having its base extending into said casing, a battery in said casing and electrically connected thereto, a pair of superimposed elongated conductor strips, an insulating strip interposed therebetween, means for connecting said strips together to form a unitary assembly, means securing one end of said assembly to the closed end of said casing to 35 electrically connect one conductor strip to said lamp base and the other conductor strip to said battery, means for securing said assembly to the side of said casing, a second insulating strip forming a part of said assembly and positioned so as to insulate said assembly from said casing, and operating means for electrically connecting said conductor strips to light said lamp.

3. The combination in a flash light of a 40 metallic casing having a substantially closed end and a lamp supported on said end, a battery, a pair of insulated conductor strips connected together to form a unitary assembly, means for securing said strips to the side of 45 said casing, means for securing one end of said assembly to the closed end of said casing in such position that said strips extend across the closed end of said casing between said lamp and said battery, and operating 50 means positioned on the side of said casing for connecting said strips to light said lamp.

4. The combination in a flash light of a 55 metallic casing having a substantially closed end and a lamp supported on said end, a battery, a pair of insulated conductor strips

connected together to form a unitary assembly, means for securing said strips to the side of said casing, means for securing one end of said assembly to the closed end of said casing on the side of said lamp opposite to 70 said first named securing means to position said strips between said lamp and battery and form a cushion therebetween, an operating member for electrically connecting said strips and a yieldable member for normally 75 rendering said member inoperative.

In testimony whereof, I have signed my name to this specification this 25th day of February 1931.

MORRIS H. BENNETT.
